UNITED STATES PATENT OFFICE

GEORGE W. GILMORE, OF WEBSTER, PENNSYLVANIA.

IMPROVEMENT IN FORCE-PUMPS.

Specification forming part of Letters Patent No. **174,904**, dated March 21, 1876; application filed August 6, 1875.

To all whom it may concern :

Be it known that I, GEORGE W. GILMORE, of Webster, Westmoreland county, and State of Pennsylvania, have invented a new and useful Improvement in Force-Pumps, of which the following is a specification :

This invention relates to an improvement on the force-pump for which Letters Patent have already been granted me; and it consists of a valve in the head of the pump, for admitting air to the barrel above the piston, where it is compressed by the upward stroke, and forced into the hollow piston, for the purpose of giving greater force to the expulsion of the liquid from the pump by the downward stroke of the piston.

The drawing exhibits a vertical section of a force-pump provided with the improved piston elsewhere described, and the valve for admitting air to the pump-barrel.

A is the pump-barrel. A' is the discharge-pipe. B is the hollow piston, and B' is the rod. C C' are valves connected together, which open and close alternately the openings a a and b b in the top and bottom of the piston, respectively, the chamber F in the piston being for the reception of the compressed air admitted by the upward stroke. G is the cap or top of the pump, provided with a stuffing-box, H, through which the rod plays. I I are openings in the cap for the admission of air. K is a stirrup attached to the under side of the cap that supports the spiral spring L, which holds the valve M in its seat to close the openings I I.

The operation of the invention is as follows : The piston B being forced down, the pressure of the air on the valve M opens it, and the pump-barrel above the piston is filled with air, which is confined there when the downward stroke is finished by the closing of the valve. When the piston is drawn upward the air in the barrel is compressed, and, the upper valves a a of the piston opening at the same time, the compressed air enters into and fills the chamber F. Now, when the next downward stroke is given, the lower valves b b of the piston are opened and the upper valves closed, confining the air, which thereupon rushes out of the valves b b, and presses on the water or other liquid, which has been raised in the pump-barrel, and this pressure of the compressed air, added to that of the piston on the liquid, forces it through the discharge-pipe A with much greater force and velocity than would be obtained by the pressure of the piston alone.

Having thus described my invention, what I claim as new, and desire to secure by Letters Patent, is—

The openings I I and valve M, in combination with the piston B, constructed substantially as described and set forth.

GEORGE W. GILMORE.
